His

UNITED STATES PATENT OFFICE.

ABRAM C. BOICE, OF KANSAS CITY, MISSOURI.

SWINGING CRIB.

1,218,363.

Specification of Letters Patent.

Patented Mar. 6, 1917.

Application filed April 19, 1913. Serial No. 762,205.

To all whom it may concern:

Be it known that I, ABRAM C. BOICE, a citizen of the United States, residing at Kansas City, in the county of Jackson and State of Missouri, have invented certain new and useful Improvements in Swinging Cribs, of which the following is a specification.

My invention relates to improvements in 10 swinging cribs.

The object of my invention is to provide a crib which may be freely ventilated but from which insects, such as flies and mosquitos may be excluded without interfering 15 with the passage to the interior of the crib of air as the crib is swung.

A further object of my invention is to provide a crib in which the springs for supporting the mattress will be protected by 20 screening, the disposition of the screening being such that the springs in use will not injure the screening material.

A further object of my invention is to provide a crib with side doors and means 25 for detachably supporting the doors in the raised or open position.

The novel features of my invention are hereinafter fully described and claimed.

In the drawings which illustrate the preferred embodiment of my invention,

Figure 1 is a perspective view of my improved swinging crib, one of the doors being shown in the open position and a portion of the other door being broken away.

Fig. 2 is a cross section of the frame, the doors being closed and the supports removed.

Fig. 3 is a horizontal section of the crib.

Similar reference characters designate 40 similar parts in the different views.

1 is a rectangular open frame the two side openings of which are adapted to be closed respectively by doors 2 to the upper edges of which are affixed hinges 3 secured 45 to the frame.

At opposite ends of the frame 1 are secured flexible swinging supports, such as chains 4, the upper ends of which may be supported by any suitable means, not 50 shown.

The lower ends of the chains are bifur-

cated and each arm thereof has secured to it short chains 5 having hooks 6 adapted to releasably engage eyes 7 provided two on the outer side of each door 2. When the 55 hooks 6 are engaged with the eyes 7, the doors will be held in the open position in which one of the doors is shown in Fig. 1.

To hold the doors closed, they may be provided each with hooks 8 adapted to releasably engage screws 9 mounted in the frame below the doors.

Across the open bottom portion of the frame 1 extend springs 11 adapted to support a mattress, not shown.

Screens 12 cover each of the doors respectively, and screens 13 cover the end and top and bottom open portions of the frame 1. The screen over the bottom portion is disposed below and out of contact 70 with the springs 11, so that while insects are excluded from passing into the crib between the springs 11, the springs will not contact with or injure the screen.

It will be obvious that the doors 2 may 75 be either retained open or closed. By completely screening the open portions of the frame, and suspending the frame so that it may be swung, the air will have free circulation through the crib without the occupant being annoyed with insects.

I do not limit my invention to the structure shown and described, as modifications, within the scope of the appended claims, may be made without departing from the 85 spirit of my invention.

Having thus described my invention, what I claim and desire to secure by Letters Patent, is:—

1. A crib comprising a frame having a 90 side opening and a door hinged at its upper edge to the frame at the upper side of the side opening, swinging supports for said frame, and a member carried by one of said supports and having a hook for detachably 95 engaging the door to hold it in the raised open position.

2. A crib comprising a frame having a side opening and a mattress support disposed horizontally with its upper surface 100 in the plane of the lower side of said opening, a swinging support for said frame, a

door hinged at its upper edge to said frame for closing said opening and adapted to be swung, when opened, to a substantially vertical position, and means attached to said support for releasably engaging said door to hold the door in the open position.

In testimony whereof I have signed my

name to this specification in presence of two subscribing witnesses.

ABRAM C. BOICE.
